ULTRA HIGH FREQUENCY TELEVISION AND RADIO INDOOR ANTENNA

Robert J. McAuley, Northboro, Mass., assignor to Parker
Metal Goods Company, Worcester, Mass., a corpora-
tion of Massachusetts

Filed Sept. 7, 1961, Ser. No. 66,635

Term of patent 14 years

(Cl. D26—14)

FIG. 1 is a front elevational view of an ultra high frequency television and radio indoor antenna showing my new design; and

FIG. 2 is a side elevational view thereof as seen from the right of FIG. 1.

I claim:

The ornamental design for an ultra high frequency television and radio indoor antenna, as shown.
